CLAIM

The ornamental design for an display screen or portion thereof with animated graphical user interface, as shown and described.

DESCRIPTION

FIG. 1 is a front view of a first image of an display screen or portion thereof with animated graphical user interface showing our new design;

FIG. 2 is a front view of a second image thereof;

FIG. 3 is a front view of a third image thereof; and,

FIG. 4 is a front view of a fourth image thereof.

The appearance of the animated images transitions between the images shown in FIGS. 1-4. The process or period in which one image transitions to another forms no part of the claimed design.

The words 'Reverb' and 'Volume' are illustrated in broken lines. The broken line showing of an electronic device and display screen illustrate environmental structure and the article of manufacture, respectively. The broken line showing of the words 'Reverb' and 'Volume' illustrate portions of the graphical user interface. None of the broken lines form part of the claimed design.

1 Claim, 3 Drawing Sheets
